CLEANING MACHINE

Marcel J. A. Zinty, New York, N. Y., assignor to
Magnus Chemical Company, Inc., Garwood,
N. J., a corporation of New York

Application June 16, 1944, Serial No. 540,593

8 Claims. (Cl. 141—1)

This invention relates to so-called cleaning machines of a character suitable for washing or otherwise treating metal parts, machines and so forth, by immersion and agitation in appropriate baths or solutions.

The primary object of the invention is an improved cleaning machine of this character which is of simple and trouble-free construction and so organized as to facilitate the handling of the work and to subject the same to a highly effective agitation. Other objects and advantages of the invention will be apparent from the following description.

In the accompanying drawing, Fig. 1 is a side elevation, partly broken out, illustrating a preferred form of the invention; Fig. 2 is a plan view; and Fig. 3 is a side elevation illustrating a modified form of actuating mechanism.

The preferred form of machine illustrated is portable, and comprises a rectangular tank generally designated 1 mounted on casters 2. Extending transversely across the ends of the tank adjacent the upper part thereof are rock shafts 3 and 4, which are conveniently journaled in the side walls of the tank. As shown, the rock shafts extend through to the outside of the tank walls where they pass through suitable bearings, designated 5, supported on rails 5' secured to the tank side walls.

Secured to and projecting inwardly from the rock shafts, i. e. in a direction away from the end walls of the tank, are a plurality of work supporting arms 6, two such arms being shown on each rock shaft. Each arm is provided with an upwardly opening recess 7 from which the work to be treated can be suspended, either directly or as below described, and in such fashion as to be readily inserted into and removed from the tank.

For many uses it is convenient to suspend the work within the tank in a foraminated carrier, or a basket as it is herein termed, such as the mesh-bottom basket 8 shown in the drawings. Such basket, otherwise of any suitable construction, is provided adjacent its ends with bails adapted for engagement with the work supporting arms 6. As shown, the bails comprise pairs of upwardly extending arms 9 pivotally attached to the side walls of the basket and united at their upper ends by cross bars 10 adapted to seat in the recesses 7 of the work supporting arms. As will be apparent, the basket is thus readily removable; also, if it is desired to load the work into the basket when the latter is in position in the tank, this can be conveniently done because

the entire open top of the basket is free of any obstruction by or from its supporting means.

Means is provided for oscillating the rock shafts in synchronism to impart a vertical, reciprocatory motion to the work suspended from arms 6; and, as will be understood, the tank will be filled with the washing or treating solution to a depth appropriate to the work in hand so as to insure an effective agitation of the work in the solution. The oscillation of the rock shafts is effected by imparting an oscillatory motion to one of them and cross-connecting such shaft to the other, so that the shafts oscillate in synchronism but in opposite, rotary directions.

15 In the preferred arrangement illustrated in Figs. 1 and 2, sprocket wheels 11 and 12 are secured to the projecting ends of rock shafts 3 and 4, respectively, and a drive chain 13 is oppositely or reversely trained on the two wheels, i. e. over wheel 11 and under wheel 12. The otherwise free end of that portion of the chain which engages wheel 12 is secured to that wheel, as at 14; and means is provided for alternately drawing upon and releasing the other end of the chain to an extent appropriate to the stroke required of the work supporting arms 6. As will be understood, the weight of the basket and its load effects the downward movement of the arms as permitted by the release of the chain. In 20 other words, the arrangement is such that the upward movement of the basket is effected by applied power and the downward movement by gravity.

The end of drive chain 13 remote from that secured to wheel 12 is attached to a crank pin 35 15 protruding from a disc 16 secured to a shaft 17. The latter is arranged to be driven by a motor 18 through suitable reduction gearing generally designed 19.

40 In the construction illustrated in Fig. 3, crank arms 20 and 21 are mounted on the ends of rock shafts 22 and 23, respectively, and arms 20 and 21 are cross-coupled by a rigid connecting rod 24. An extension of crank arm 20 provides a 45 driving crank arm 25 which is actuated by rod 26, crank pin 27, disc 28 and shaft 29. As above, shaft 29 is driven by a motor 18 through reduction gearing 19. All other parts of the apparatus are as already described and are correspondingly numbered.

In the light of the foregoing description the following is claimed:

1. In a washing machine the combination with a tank, of a basket therein, hanger members 55 standing from the corners of the basket and piv-

totally connected thereto, a cross bar extending transversely above each end of the basket and each uniting a pair of hanger members, two transverse, horizontally disposed rock shafts journaled in the side walls of the tank beyond the ends of the basket, a pair of inwardly projecting supporting arms mounted on each rock shaft and having upwardly opening recesses to receive and removably support said cross bars, means mounted on the outside of the tank for oscillating one of the rock shafts, and cross-connections therefrom to the other rock shaft to oscillate the same in synchronism with the first rock shaft to impart a vertical reciprocatory motion to the basket through said supporting arms.

2. In a washing machine the combination with a tank, of a basket therein, hanger members upstanding from the corners of the basket and pivotally connected thereto, a cross bar extending transversely above each end of the basket and each uniting a pair of hanger members, two transverse, horizontally disposed rock shafts journaled for support beyond the ends of the basket, inwardly projecting supporting arms mounted on each rock shaft and having upwardly opening recesses to receive and removably support said cross bars, and means for oscillating said rock shafts in synchronism to impart a vertical reciprocatory motion to the basket through said supporting arms.

3. In a washing machine the combination with a tank, of a basket therein, hanger members upstanding from the corners of the basket, a cross bar extending transversely above each end of the basket and each uniting a pair of hanger members, two transverse, horizontally disposed rock shafts journaled for support beyond the ends of the basket, inwardly projecting supporting arms mounted on each rock shaft and having upwardly opening recesses to receive and removably support said cross bars, and means for oscillating said rock shafts in synchronism to impart a vertical reciprocatory motion to the basket through said supporting arms.

4. In a washing machine the combination with a tank, of a basket therein, hanger members upstanding from the corners of the basket and pivotally connected thereto, a cross bar extending transversely above each end of the basket and each uniting a pair of hanger members, two transverse, horizontally disposed rock shafts journaled for support beyond the ends of the basket, inwardly projecting supporting arms mounted on each rock shaft and adapted to receive and support said cross bars, and means for oscillating said rock shafts in synchronism to impart a vertical reciprocatory motion to the basket through said supporting arms.

5. In a washing machine the combination with a tank, of a basket therein, hanger members upstanding from the corners of the basket and pivotally connected thereto, a cross bar extending

transversely above each end of the basket and each uniting a pair of hanger members, two transverse, horizontally disposed rock shafts journaled in the side walls of the tank beyond the ends of the basket, a pair of inwardly projecting supporting arms mounted on each rock shaft and having upwardly opening recesses to receive and removably support said cross bars, a sprocket wheel mounted on the end of each rock shaft, a chain reversely trained over said sprocket wheels and secured at one end to one of said wheels, and means for alternating drawing on and releasing the other end of the chain to raise and lower the basket.

10 6. In a washing machine, the combination with a tank, of a horizontal rock shaft disposed across the tank adjacent each end thereof, inwardly projecting supporting members mounted on the rock shafts, bail-receiving recesses on said members, a basket within the tank and of an over-all length less than the distance between the rock shafts, a bail upstanding from adjacent each end of the basket and removably engaged with the said recesses, and means for oscillating said rock shafts in synchronism to impart a vertical reciprocatory motion to the basket through said members and bails.

20 7. In a washing machine the combination with a tank, of a basket therein, hanger members upstanding from the corners of the basket, a cross bar extending transversely above each end of the basket and each uniting a pair of hanger members, two transverse, horizontally disposed rock shafts journaled for support beyond the ends of the basket, inwardly projecting supporting arms mounted on each rock shaft and having upwardly opening recesses to receive and removably support said cross bars, the free ends of said supporting arms terminating adjacent said recesses and engaging the said cross bars on the outer sides of the hanger members to provide free access to the entire open top of the basket, and means for oscillating said rock shafts in synchronism to impart a vertical reciprocatory motion to the basket through said supporting arms.

30 8. In a washing machine the combination with a tank, of a basket therein, hanger members upstanding from the corners of the basket, a cross bar extending transversely above each end of the basket and each uniting a pair of hanger members, two transverse, horizontally disposed rock shafts journaled for support beyond the ends of the basket, inwardly projecting supporting arms mounted on each rock shaft and having upwardly opening recesses to receive and removably support said cross bars, the said supporting arms engaging extended portions of said cross bars beyond the sides of the basket, and means for oscillating said rock shafts in synchronism to impart a vertical reciprocatory motion to the basket through said supporting arms.
